United States Patent Office

Des. 188,379
Patented July 12, 1960

188,379

CONSOLE FOR A DATA PROCESSING SYSTEM

Walter S. McCormick, Jr., Poughkeepsie, N.Y., assignor
to International Business Machines Corporation, New
York, N.Y., a corporation of New York

Filed Mar. 21, 1960, Ser. No. 59,807

Term of patent 14 years

(Cl. D26—5)

FIG. 1

Des. 188,379

PAGE 2

FIG. 2

Des. 188,379

PAGE 3

FIG. 3

FIG. 4

FIG. 5

Fig. 1 is a front elevation of a console for a data processing system showing our new design.

Fig. 2 is a rear elevation thereof.

Fig. 3 is a plan view.

Fig. 4 is a left hand side elevation view and

Fig. 5 is a right hand side elevation view.

The drawing figures have been shaded to indicate contrast in appearance.

I claim:

The ornamental design for a console for a data processing system, as shown and described.
